UNITED STATES PATENT OFFICE.

THOMAS E. CLARK AND JAMES E. CLARK, OF DETROIT, MICHIGAN, ASSIGNORS TO
CONTINUOUS TRAIN CONTROL CORPORATION, OF DETROIT, MICHIGAN, A CORPO-
RATION OF MICHIGAN.

TRAIN-CONTROL SYSTEM.

Application filed July 17, 1925. Serial No. 44,139.

This invention relates to the control of railway trains by means of high-frequency oscillating currents propagated in or impressed upon the rails at intervals along the 5 track by means of transmitters and circuits between the transmitters and the track and current sources respectively, which instrumentalities are preferably associated with block signal systems along the track, and its 10 object is to provide a system of this character whereby one of three signals on a locomotive is provided with energizing current whenever the locomotive passes along a portion of track in which a current is propagated 15 having a wave length which is predetermined for track conditions which are to be indicated by that particular signal, such wave lengths varying according to the occupancy of the three blocks of track in advance.

Another object of this invention is to provide a brake mechanism for the locomotive and electrically controlled means for determining the operation thereof, three circuits 25 therefore, a governor operatively connected to the locomotive to open and close a plurality of the circuits according to the speed of the locomotive, and means responsive to the currents in the track rails for selecting 30 one of the three circuits to said electrically controlled means.

The train control system hereinafter described is of the same general character as that shown and described in our Patent No. 35 1,712,788, dated May 14, 1929, and shown in the drawings associated with a signal system of the "three-lamp approach-light" type connected to rails divided into blocks, but it is to be understood that our invention is 40 not limited to use in connection with a signal system of this character, but may be used with any desired type of signal system or may be used without signal lamps.

This invention consists of a system of control stations, each embodying an electron or vacuum tube containing a filament which receives current of comparatively low voltage, the tube being connected in an oscillating circuit embodying fixed and variable 45 condensers and inductances and means to modify the circuit so that it will transmit currents of three different wave lengths to the track, one, which is hereafter termed the "danger" current, when the next or second 50 track section in advance is occupied; a sec-

ond, which is hereafter termed the "caution" current, when these two are unoccupied and the third section in advance is occupied; and a third, which is hereafter termed the "clear" current, when these three sections are 60 unoccupied, and in connection with such track and the control stations, it comprises an installation upon a locomotive embodying collector coils for cutting magnetic lines of force corresponding to the several currents 65 so as to create oscillating electric currents in the circuits of said coils, each circuit being tuned to the wave lengths of one of said currents, a signal for each collector coil circuit and adapted to receive current when its 70 coil is energized by the magnetic lines of force produced by the track current to which it is tuned, and in a normally inoperative brake mechanism which is caused to operate when either of two predetermined currents is 75 propagated in the track.

The invention also consists in collector coil circuits which each embody a thermo-junction whereby the oscillating current created in such circuit may be converted, and a polar 80 relay controlled by a plurality of the thus converted currents adapted to select the circuit between a current source and one or the other of two of said signals according to the current in the track rails.

It also consists in a normally closed circuit between a current source and an electro-pneumatic valve connected into the air brake system of the locomotive, which circuit is opened when one or the other of two 90 of said collector coil circuits is energized, manually operable means, and an additional circuit adapted to be closed by said means to carry current from the current source to said electro-pneumatic valve and thereby 95 prevent the application of the brakes.

It also consists in a governor operatively connected to the locomotive and adapted to open two of the circuits to said electro-pneumatic valve, one after the other, when the locomotive exceeds the speeds predetermined 100 for "danger" and "caution" conditions at the control stations of the blocks of track occupied by the locomotive.

It further consists in the details of construction illustrated in the accompanying drawings and particularly pointed out in the claims.

In the drawings, Fig. 1 is a diagram of a track signal station combined with our novel 110

control station installation and a diagram of the instrumentality on the locomotive adapted to co-operate with the control station installation, the parts of the locomotive installation being in the positions they assume when responding to "clear" current in the track occupied by the locomotive. Figs. 2 and 3 are diagrams of these locomotive instrumentalities when responding to "caution" and "danger" currents in the tracks, respectively. Fig. 4 is a diagram of a transmitter mechanism.

Similar reference characters refer to like parts throughout the several views.

15 The signal and train control installations positioned along the track which are shown in Fig. 1 are substantially the same as those shown in our co-pending application Serial Number 36,628, filed June 12, 1925, and the 20 transmitter shown in Fig. 4 is the same as the transmitter shown in Fig. 3 of that application. The speed governor shown conventionally in Figs. 1, 2 and 3 is preferably that shown in our Patent No. 1,563,075, 25 granted November 24, 1925. The signal installations, with which our novel train control installations are combined, as described in the first of the above named prior applications, embody lamp stands provided with 30 three signal lamps, preferably green, yellow and red, which indicate how the track in advance is occupied, the green lamp showing that the two blocks in advance are unoccupied, at which time the parts of the 35 signal installation are said to be in "clear" positions; the yellow lamp showing that the second block in advance is occupied, at which time the parts of the signal installation are said to be in "caution" position; and the red 40 lamp showing that the next block in advance is occupied, at which time the parts of the signal installation are said to be in "danger" position. The lamps are respectively termed "clear", "caution" and "danger" lamps. The 45 track illustrated is that of one of two parallel tracks, each of which is set apart for traffic in one direction which is considered to be from right to left in Fig. 1. The blocks and the stations therefor are lettered B and 50 C, and block B is supposed to be occupied while the three blocks in advance are unoccupied. For this reason, the parts of station B are in "clear" position.

Relays are shown in the drawings, each 55 provided with one or more armatures designated by small letters, and in the following description, the armatures will be designated by their respective letters following the numeral designating the relay to which they belong. Where such procedure is of advantage, a part of a station installation may be further designated by using the letter of its block or station together with the numeral of the part. The next station in the rear is 60 referred to as station A, while the stations 65

in advance as stations C, D and E, but none of these are shown, but they would be identical with station B shown in the drawings.

The rails 1 and 2 are divided into blocks by insulations 3 in the usual manner and adjacent the exit end of each block is a lamp stand 4 provided with red, yellow and green lamps. Adjacent each station and in part controlling it is a track relay 7 connected to the rails at the exit end of the block by 75 wires 5 and 6. These relays are energized by track batteries 8 which connect to the rails at the entrance ends of the blocks by means of wires 9 and 10, resistances 11 being used to prevent damage to the batteries 80 when the rails are short-circuited by means of the axles of rolling stock.

At each station is a signal battery 12 which connects to its lamp stand, whenever its block is occupied, by wire 13, armature 7^c 85 and wire 15. The return circuit is controlled by the polar-neutral relay 14 which is energized by current from the battery 12 of the next station in advance, the current coming in over wire 16C. When no current comes 90 in over wire 16C, relay 14 is de-energized; if positive current comes over this wire, polar armature 14^a is swung clockwise; and if negative current comes over wire 16, armature 14^b is swung counterclockwise. No 95 current passes to the signal lamps when relay 7 is energized and this relay is always energized except when its block is occupied.

The direction of current in each wire 16 depends upon the occupancy of the block 100 from which it extends rearwardly and upon the occupancy of the next two blocks in advance. With block E occupied, relay 7E is de-energized and its armature *b* opens the circuit of wire 16 of block E so that no current flows to relay 14 of station D. Block D being unoccupied, relay 7D is energized but 14D is de-energized. Negative current therefore flows from the negative end of battery 12D over adjacent wires 13 and 25, 110 armature 14^a, wire 26, armature 7^b and wire 16D to relay 14C and back over wires 23D and 24, armature 14^b and wires 21 and 20 to battery 12D.

Relay 14C being negatively energized positive current flows from the positive end of battery 12C over adjacent wire 20, armature 14^a, wire 26, armature 7^b (block C being unoccupied, this relay is energized) and wire 16C to relay 14B and back over wires 23C 120 and 24, armature 14^b and wires 25 and 13 to battery 12C. When no current flows to a station over wire 16, the parts assume the danger position and as soon the block of that station is occupied, current flows to the 125 red or "danger" lamp over wires 20 and 21, armature *c* of de-energized relay 14 and wire 17, and from the lamp stand over the common wire 15, armature 7^c and wire 13 to the battery. When negative current flows to 130

relay 14 over wire 16, current flows over wires 20 and 21, armature 14^a, wire 22, armature 14^a and wire 18 to the yellow lamp, and back to the battery as before described.

- 5 When positive current flows to relay 14, its armature *d* swings to the position shown in Fig. 1 and current flows over wire 19 to the green lamp G. The current from the relay 14B returns over wire 23C, and over wire 24, 10 armature 14^b and wires 25 and 13 of station C.

When relay 14 of station B is de-energized, which occurs when block C next in advance is occupied, it is by reason of the 15 relay 7 of station C being de-energized and opening the circuit between battery 12C and wire 16C at armature 7^b. In that case, current flows from the negative of battery 12B over wires 13 and 25, armature *a* of de-energized relay 14, wire 26, armature *b* of normally energized relay 7B, and wire 16B to relay 14A.

If relay 14 of station B receives any current over wire 16C and block B is unoccupied, 25 current flows from the positive of battery 14B over wire 20, armature 14^a, wire 16, armature 7^b to wire 16B. The return is controlled by armature 14^b as before described.

- 30 In Fig. 1, the circle 30 indicates the transmission device for propagating high-frequency oscillating currents of different wave lengths in the rails. Current is conducted to this device by means of the wire 63, which 35 connects to the wires 20 and 21, and returns over the wire 64 connected to the wires 15 and 13 via armature 7^c in its dropped position. It is therefore evident that no current flows to the transmitter unless the relay 40 7 is de-energized, that is, unless the block to which the transmitter is connected is occupied. This again makes for saving of battery current.

45 The current transmitter.

As indicated in Fig. 4, the wires 63 and 64 connect to a motor generator 65 and to the filament 66 of a vacuum or electron tube 67, an adjustable resistance 68 being provided 50 in the filament circuit to control the temperature of the filament. The wire 64 is also the conductor of the high voltage from one side of the motor generator 65 to the grid coil 80, which connects to the grid 72 by means of the wire 69, grid leak 70 and condenser 71. The wire 73 from the other side 55 of the motor generator connects to the plate coil 74 which connects to the plate 75 by means of wire 76. This coil is shunted by the variable condenser 77 whereby the oscillations are transmitted to the rails 1 and 2 by means of the wires 78 and 79 from the loading coil 81, the wires 78 and 79 preferably connecting to the wires 5 and 6. These 65 oscillations are those which are transmitted

when the next or second block in advance is occupied, that is, are of the "danger" wave length. A condenser 82 is shown connected into the wire 78 to prevent short circuiting of the direct current from battery 8 by the 70 coil 81.

The polar-neutral relay 83 is energized by current received from the second station in advance over wire 84, and the neutral armature 83^a connects the wire 85, which shunts 75 the plate coil 74, to the polar armature 83^b which is swung clockwise by a positive current over wire 84, under which condition the additional condenser 86 and wire 88 are brought into the circuit of this plate coil 86, 74, and this polar armature is swung counterclockwise by a negative current over this wire, when the second condenser 87 and wire 89 are brought into this shunt circuit. The shunt circuit embodying the condenser 86 so 85 influences the current transmitter that "clear" wave lengths are propagated in the rails, and the circuit embodying the condenser 87 causes oscillations of a "caution" wave length.

Connected into the wire 79, extending from the transmitter 30 to the rails is a relay 90 which responds to these high-frequency currents, and attracts its armature *a*, closing a circuit to the slow release relay 92, said circuit consisting of wires 64 and 93, armature 90^a, wire 94, relay 92, and wire 95 to wire 63. The energized relay 92 attracts its armatures. As soon as the train T leaves block B, relay 90 becomes deenergized, but relay 7 becomes energized, and a circuit is completed over wires 20, 21, 63 and 95 to the relay and wire 94, armature 92^a, wire 96, armature 7^c and wire 13 to the battery, and it remains so until its block is 100 again occupied, when the first described circuit to this relay is again closed. The relay 92 being slow acting, it holds its armatures during this change of circuits.

The relay 83 receives no current when 110 either of the two next blocks in advance is occupied. It receives negative current when the third block in advance is occupied and the first and second are unoccupied. It receives positive current when the three 115 blocks in advance are unoccupied, and if we refer to station B, its relay 83 receives no current when relay 7 of either block C or D is de-energized. It receives negative current when relays 7 of these two blocks 120 are energized and relay 14 of station D is de-energized. It receives positive current when relay 14D is energized by either positive or negative current from station E. The circuit from any station which controls 125 relay 14 of the next station in the rear has already been traced.

Starting with the three blocks in advance of station B unoccupied, current from positive of battery 12 of station D flows over its 130

wire 20, armature 14^a, wire 26, armature 7^b, wire 16D to station C, thence over its wire 97, to wire 23C to station B, thence over wire 98 of this station, armature 7^a, (block 5 B being occupied) wire 84 to relay 83, thence over wire 29D to block C and armature 92^b thereof, and over wire 99, armature 7^a, wire 98 to wire 23D, and over this wire 10 to station D, and over its wire 24, armature 14^b, and wires 25 and 13 to the battery.

If block E were occupied, current would flow from negative of battery D12 over wires 13 and 25 to armature *a* of de-energized relay 14 of station D, and thence over 15 the above described circuit to relay 83B. The return is the same until station D is reached when the current flows from wire 24 over armature 14^b, wires 21 and 20 to positive of battery 12. These two circuits 20 include armatures *b* of relay 7D and *a* of relay 7C, which relays must be energized to hold these armatures in their circuit closing positions, so that, if either block D or block C is occupied, the relay 7 connected thereto will be de-energized and the energizing circuit to relay 83B will be opened, resulting in current of "danger" wave length being propagated in block B.

The length of track in which these currents are effective for affecting the instrumentalities on the locomotive will vary with the character of the current, but such lengths are preferably less than the lengths of the block sections so that there will be 30 comparatively neutral or non-energized lengths of track between energized lengths which are preferably at the entrance ends of the blocks adjacent the signal installations. These non-energized sections permit certain 35 of the instrumentalities on the locomotive to assume neutral positions for reasons which will be apparent later on.

The currents propagated in the rails produce strong fields of magnetic flux just in 45 front of the leading axle of the locomotive traveling the energized zone, and the lines of force probably pass around the rails and around the axle and bridge the gaps between the rails and axle by means of the 50 wheels. We have found that a very strong field exists just in front of the wheels of the leading axle.

The locomotive installation.

55 Mounted on the locomotive at an oblique angle to the rails and just in front of the leading axle of the locomotive in the strong fields of magnetic flux are three collector coils 100G, 100Y and 100R, connecting to 60 thermo-junctions 101G, 101Y and 101R and to variable condensers 102G, 102Y and 102R respectively. The circuits of these coils are 65 tuned to respond to the magnetic flux produced by the currents whose wave-lengths denote "clear," "caution" and "danger" po-

sitions in the control stations of the tracks occupied by the leading axle, to denote the conditions of the track in advance. The thermo-junctions or heater-current-converters may be of any desired type and convert 70 the currents of the collector coils and it will be assumed that current passes from the thermo-junction 101R over the wire 105 to relay 103 and back over wire 106. The relay 103 when energized attracts its armature *a*. Current from the thermo-junction 101Y passes over the wire 106 to polar relay 104 and back over wire 107, causing the relay 104 to swing its armature counter-clockwise while current from the thermo-junction 101G travels this path in the opposite direction and causes armature 104^a 80 to swing clockwise.

When the parts are as shown in Fig. 1, current flows from battery 108 over wire 85 109, armature 104^a, wire 110, relay 111, wires 112 and 113 to the battery. It also flows over wires 109 and 114, armature *a* of relay 117 in dropped position, wire 115, armature 111^a and wire 116 to green lamp 118 and 90 wires 119 and 113 to the battery.

When the parts are as shown in Fig. 2, current flows from the battery over wire 109, armature 104^a, wire 120, relay 117 and 95 wire 121 to the battery. It also flows over wire 114, armature 117^a and wire 123 to yellow lamp 124 and wires 119 and 113 to the battery.

When the parts are as shown in Fig. 3, current flows over wires 109 and 114, armature 117^a, wire 115, armature 111^a and wire 126 to red lamp 127, and wires 119 and 113 to the battery. The lamps on the locomotive will therefore indicate the wave lengths of the currents propagated in the rails of 105 the block then occupied by the leading wheels.

The brake mechanism comprises a solenoid 130, which, when de-energized, permits 110 automatic application of the brakes as hereinafter described, but while energized, prevents such application. The circuit to this solenoid under "clear" conditions (Fig. 1) is over wires 109 and 114, armature 117^b, wire 131, armature 111^b and wires 132 and 115 133 to the solenoid, thence over wires 119 and 113 to the battery.

The speed governor is indicated by the circle 146 and embodies two arms 142 and 138 connected to the wires 139 and 140 respectively, which move out of engagement with the contacts at the end of the wire 141, the arm 142 when the locomotive exceeds the speed predetermined for "danger" conditions, say four miles per hour, and the arm 138 when the locomotive exceeds the "caution" speed, say twenty miles per hour.

Current normally flows to the solenoid so long as relay 117 is de-energized and relay 111 is energized. But when relay 117 is 130

energized, which occurs when armature 104^a closes the circuit over wire 109, armature 104^a, wire 120, relay 117 and wires 121 and 113, which occurs when collector coil 100Y carries current, or when relay 111 is de-energized, which occurs when relay 103 is energized by current from coil 100R and opens the circuit over wire 109, armature 103^a, wires 135 and 136, armature 117^c, wire 137, armature 111^c and wire 110 to the battery, the circuit to the solenoid 130 is broken and the brakes will be applied automatically unless the engineer and fireman are alert and depress the forestalling keys and the engineer operates his brake valve to bring the speed of the train down to that indicated by the signal lamps. If the yellow lamp burns, as indicated in Fig. 2, the forestalling keys 143 and 144 may be depressed, and as soon as the train speed has been reduced to that predetermined for "caution" conditions, the circuit closed by these keys will be over wires 109 and 114, armature 117^b, wire 139, arm 142, wire 141, wire 147, key 144, wire 145, key 143, wire 148, relay 149 and wires 150 and 113 to the battery. The energized relay 149 attracts its armatures and closes two circuits, one between the wires 141 and 148 by way of its armature ^a and wire 152, which carries current so that this relay remains energized until the speed is increased beyond that predetermined for "caution", or until a "danger" current is picked up by coil 100R, when relay 117 becomes de-energized.

The second circuit closed by this relay 149 upon depression of the keys is between the wires 133 and 141 through the medium of armature 149^b, so that the solenoid 130 will again receive current and continue to receive it until the circuit between wires 139 and 141 is opened by the "caution" arm 142 of the governor, or until the "danger" coil 100R picks up current.

When this occurs the circuit to relay 117 is opened by armature 103^a and the circuit from the battery to the "caution" arm 142 of the governor is opened by armature 117^b. But this armature 117^b closes a circuit over wire 131, armature 111^b and wire 140 to the "danger" arm 138 of the governor. When armature 117^b dropped, it opened the circuit to relay 149, as shown in Fig. 3, so that solenoid 130 is de-energized. The engineer must now bring his train down to "danger" speed, at which time the "danger" arm 138 of the governor closes the circuit between wires 109 and 147. If the two keys 143 and 144 are now depressed, a circuit to the relay 149 is again closed so that the solenoid may again be energized. The second circuit to this relay is again established by armature 149^a.

As soon, however, as the locomotive leaves a "caution" or "danger" track section and

enters a "clear" section, current will again pass to relay 111, which is provided with three armatures, one to close the circuit to the green lamp, the second to close the circuit to the solenoid, and the third to close an auxiliary circuit for the relay itself.

It will therefore be seen that as the train is running along under "clear" conditions, a green lamp will burn steadily in the cab. The circuit to the green lamp 118 is as follows: from the battery 108 over wire 114, dropped armature 117^a, wire 115, armature 111^a, wire 116, lamp 118 and wires 119 and 113. The relay 111 is kept energized by its stick circuit from battery 108 over wire 109, dropped armature 103^a, wires 135 and 136, dropped armature 117^c, wire 137, armature 111^c, wire 110, relay 111, and wires 112 and 113 until relay 104 is negatively energized by current picked up by coil 100Y, resulting in relay 117 being energized, or until relay 103 is energized by current picked up by coil 100R. As soon as the train enters a track section carrying "caution" current, the green lamp will be extinguished and the yellow lamp burn. The circuit to the solenoid will be de-energized and remain so until the train is brought to "caution" speed and the two forestalling keys are depressed. The train may now go ahead at "caution" speed until it enters a "danger" section, whereupon it must be slowed down to "danger" speed. If the engineer fails to slow his train and if either he or the fireman fails to depress his forestalling key, the brakes will be automatically applied and the train brought to a stop.

While any desired type of valve mechanism may be employed, that shown conventionally in Figs. 1, 2 and 3 has been found available. The well known engineer's valve 155 is employed to admit air from a pressure tank to the train pipe 156 to release the brakes and to relieve the pressure in this pipe to cause application of the brakes. The valve 157 is connected to the core of the solenoid 130 and normally prevents flow of air from the pipe 158, connecting to the main pressure tank. But when this valve drops, as shown in Figs. 2 and 3, air flows through the pipes 159 and 160 to the cylinders 161 and 162.

A piston 163 is slidable in the cylinder 161 and connects to a valve 164, which, when air under pressure is admitted to the cylinder 161, is forced to the right in Fig. 1 and closes the main passage from the valve 155 to the train pipe, thus preventing increase of the train pipe pressure. It may be decreased, however, as the check valve 165 permits air to flow from the train pipe to the valve 155.

The pipe 158 connects to the valve chamber 167 by means of a pipe 168 and this chamber embodies a cylinder 169 for the piston 170, to which is connected a valve 171

which normally prevents the discharge of air from the small orifice 172. A second cylinder 162 contains a piston 174 which connects to the valve 175 by means of a hollow rod 176 so that when in the position shown in Fig. 1, air from the pipe 168 fills the space on both sides of the piston 170, but when the parts are moved to the positions shown in Figs. 2 and 3 by reason of air under pressure from the pipe 159, air from above this piston 170 flows to the vent 177 through the holes 178 in the hollow rod 176. A reservoir 180 is connected into the valve chamber in order to store sufficient air 10 to make the reduction in pressure above the piston 170 comparatively slow and thus allow ample time for the return of the electro-pneumatic valve to normal position upon the depression of the forestalling keys, as above explained, before the train pipe pressure is reduced sufficiently by the escape of air from the small orifice 172 to cause application of the brakes. But when the air above the piston 170 is sufficiently 20 reduced, the pressure below this piston will lift it together with the valve 171 and the air in the train pipe will escape from the orifice 172 and the brakes will be applied. The pressure in the cylinders 161 and 162 escapes through the vent 181 as soon as the 30 electro-pneumatic valve is returned to normal position by the solenoid 130.

The present invention does not include the valve mechanism or any of the other details 35 beyond the solenoid 130, and any other desired device may be substituted therefor by those skilled in the art of railway brakes. Neither does the present invention comprise the details of the relays, armatures, lamps 40 or current transmitters and we therefore do not wish to be limited to any of the details of construction. Where the word "locomotive" is employed, we wish to include all types of automotive vehicles equipped with 45 power brakes of whatsoever character the automatic application of which may be brought about or prevented by means of a solenoid of the character described.

We claim:

50 1. In a train control mechanism adapted to be installed upon a locomotive equipped with power brakes and adapted to travel on rails to which control stations are connected at intervals along the track for the purpose 55 of propagating therein electric currents of three different wave lengths according to the condition of the track in advance, the combination of three electric signals, a current source, circuits between the signals and the current source, a pair of relays to control 60 said circuits, and a collector coil and a circuit therefor tuned to respond to each of said currents in said track, one of said relays being a neutral relay and connected 65 to one collector coil circuit and another re-

lay being a polar relay and connected to the two other collector coil circuits.

2. In a train control mechanism adapted to be installed upon a locomotive equipped with power brakes and adapted to travel 70 on rails to which control stations are connected at intervals along the track for the purpose of propagating therein electric currents of three different wave lengths according to the condition of the track in advance, the combination of a current source, an electro-pneumatic valve controlling said power brakes, a circuit between the current source and valve to energize the valve to prevent automatic application of the brakes, 75 a neutral relay to keep said circuit closed, an energizing circuit for said relay, a polar relay controlling said energizing circuit, two collector coils and circuits therefor tuned to respond to said currents in said track, 80 and conductors connecting said collector coil circuits to said polar relay, said relay being energized by current from one coil circuit to close the energizing circuit to said neutral relay and by the current from the other coil circuit to open said energizing circuit.

3. In a train control mechanism adapted to be installed upon a locomotive equipped with power brakes and adapted to travel on 95 rails to which control stations are connected at intervals along the track for the purpose of propagating therein electric currents of three different wave lengths according to the condition of the track in advance, the combination of a current source, an electro-pneumatic valve controlling said power brakes, a circuit between the current source and valve to energize the valve to prevent 100 automatic application of the brakes, a neutral relay to keep said circuit closed, an energizing circuit for said relay, a polar relay controlling said energizing circuit, two collector coils and circuits therefor tuned to respond to said currents in said track, 105 conductors connecting said collector coil circuits to said polar relay, said relay being energized by current from one coil circuit to close the energizing circuit to said neutral relay and by the current from the other coil circuit to open said energizing circuit, 110 and manually operable means to close said second circuit.

4. In a train control system for railways 115 having tracks divided into blocks and means to propagate high-frequency currents of three different wave lengths in the rails of the several blocks, depending upon the presence and proximity of the next train ahead, a signal apparatus on the vehicle embodying three lamps, a current source, circuits between said current source and said lamps, and control means responsive to the electric 120 energy in the track rails for rendering one 125 130

or the other of said lamps effective, said control means embodying three collector coils and circuits therefor positioned adjacent but spaced from the rails.

5. In a train control system for railways having tracks divided into blocks and means to propagate high-frequency currents of three different wave lengths in the rails of the several blocks, speed control apparatus 10 on the vehicle including means permitting the vehicle to proceed at maximum speed and other means permitting the vehicle to proceed at two restricted speeds, and control means responsive to the electric energy in 15 the track rails for rendering one or the other of said means effective depending upon the proximity of the next train ahead, said control means embodying three collector coils and circuits therefor positioned adjacent to 20 but spaced from the rails, current transformers to change oscillating currents to direct currents, and relays energized by said direct currents.
6. In a train control system for railways 25 having tracks divided into blocks and means to propagate high-frequency currents of three different wave lengths in the rails of the several blocks, speed control apparatus on the vehicle including a current source, an 30 electro-pneumatic valve, circuits therefor of which one permits the vehicle to proceed at maximum speed, and speed responsive means permitting the vehicle to proceed at two restricted speeds and adapted to open 35 the circuits to the electro-pneumatic valve when the selected predetermined speed is exceeded, and control means responsive to the electric currents in the track rails and including a collector coil for each of said 40 wave lengths for rendering one or the other of said speed responsive means effective.
7. In a train control system for railways 45 having tracks divided into blocks and means to propagate high-frequency currents of three different wave lengths in the rails of the several blocks, speed control apparatus on the vehicle embodying a normally closed electro-pneumatic valve adapted to open when de-energized to cause the application 50 of brakes, a current source to energize said valve, three collector coils and circuits therefor mounted adjacent to and spaced
- apart from the track rails, each circuit being responsive to one of the electric currents propagated in the rails, relays connected to 55 and influenced by said collector coils, a normal circuit between the current source and said valve adapted to be closed when one of said collector coils is energized and to be opened when either of the other two coils 60 is energized, two additional and normally open circuits between the current source and said valve, manually operable means to close said circuits, and speed responsive means connected into said additional circuits and 65 adapted to open them as the vehicle exceeds the speeds determined therefor.
8. In a train control system for railways having tracks divided into blocks and means for propagating high-frequency currents of 70 three different wave lengths in the rails of the several blocks according to the condition of the track in advance, the combination of a current source on a vehicle, speed control apparatus on the vehicle adapted to permit 75 the vehicle to proceed at maximum, minimum and intermediate speeds, and means on the vehicle responsive to the electric energy in the track rails and comprising a collector coil for each of said currents to 80 control the operation of said speed control apparatus and thereby cause the vehicle to respond in speed to the current in the track rails.
9. In a train control system for railways 85 having tracks divided into blocks and means for propagating high-frequency currents of three different wave lengths in the rails of the several blocks according to the condition of the track in advance, the combination of a current source on a vehicle, speed control apparatus on the vehicle adapted to permit 90 the vehicle to proceed at maximum, minimum and intermediate speeds, and means on the vehicle responsive to the electric energy 95 in the track rails and including current receptive means adjacent said rails to control the operation of said speed control apparatus and thereby cause the vehicle to respond in speed to the current in the track 100 rails.
